MAURICE MOORE, OF MELBOURNE, AND JOHN MURRAY, OF GEELONG WEST, VICTORIA,
AUSTRALIA.

ROTARY PUMP.

No. 889,949.

Specification of Letters Patent.

Patented June 9, 1908.

Application filed July 12, 1906. Serial No. 325,804.

To all whom it may concern:

Be it known that we, MAURICE MOORE and JOHN MURRAY, subjects of the King of Great Britain and Ireland, and residents of 178 5 Bellair street, Kensington, in the city of Melbourne, in the county of Bourke, and 118 Upper Hope street, in the town of Geelong West, in the county of Grant, respectively, both in the State of Victoria and Commonwealth of Australia, have invented certain new and useful Improvements in Rotary Pumps, of which the following is a specification.

The object of our invention is to provide 15 a mechanism for pumping air, gas, water or liquids or semi liquids of any character. In the past a variety of devices have been used to this end, but with our invention a cheap and simple pump is produced having but few 20 wearing parts and absorbing but little power.

Referring to the drawings which form a part of this specification Figure 1 is an elevation partly in section of our pump. The driving tongue being at the top. Fig. 2 25 is a view of the discharge end of our casing and pumping disk. The bracket discharge cover and the ring are removed and both the casing and the pumping disk occupy the same relative position that they do in Fig. 1. 30 Portion of the pumping disk is broken away to show the passage-ways from the ports to the tubular spindles. Fig. 3 is an interior view of part of the casing, and is similar to Fig. 2 except that the pumping disk, driving 35 tongue and suction ring are removed. Fig. 4 is a plan of the pumping disk showing the suction and discharge ports and the outer end of the driving tongue between them. Fig. 5 is a plan on a reduced scale of the suction 40 ends of two pumps when placed together.

Similar letters of reference indicate similar or corresponding parts where they occur in the several views.

Our invention includes a base plate A 45 above each end of which upstands a bracket. One of these is called the suction bracket B and the other the discharge bracket C. Protruding horizontally from the inside of each 50 bracket and near the top of the same is a boss D. Through each boss and eccentric with the same is an eccentric spindle bearing hole E.

Protruding from the outside and near the 55 top of each bracket and concentric with the

spindle bearing hole before referred to is a stuffing box F. In this is a gland G or in lieu of there being a gland adjusted by studs and nuts as shown, an internally threaded nut gland may be used. The outer ends of 60 each of the said glands protrude and are either threaded internally or externally to receive connections G³.

Turning around each boss before referred to is a cover plate. There are thus two cover 65 plates, and the suction one is marked H and the discharge one J. Each cover plate is prevented from moving outwardly upon the said boss by a shoulder K. It is prevented from moving inwardly by a leather washer L 70 which is secured to the boss D by a holding plate M. This holding plate M is fixed to the said boss by screws N (Fig. 3) or other means. The said leather washer L is larger in diameter than the holding plate M and surrounding 75 the enlarged portion is a locking or jointing ring P. Each one of these rings P, by screws Q or other means, is secured to its cover plate and turns or rotates with it. The leather washer and the holding plate each have an 80 eccentric hole therethrough of approximately the same diameter as the eccentric hole E before referred to.

Freely turning in each eccentric spindle bearing hole is a tubular spindle. One of 85 these is hereinafter called the suction spindle R and the other the discharge spindle S. The outer end of each spindle passes into the stuffing box F before referred to and turns therein. The inner ends of the spindles are 90 connected to or are integral with a pumping disk T which may be centrally situated between the said two spindles. The width of the said pumping disk as also its diameter will depend upon conditions. In its circumference are two ports, the suction port U and the discharge port V (see Figs. 2 and 4). Between the said suction port U and the tubular suction spindle R is a suction passageway W (see Fig. 2). Between the said discharge 100 port V and the tubular discharge spindle S is the discharge passageway X (see Fig. 2).

Between the two ports U and V before referred to and through the disk T is drilled a hole Y (see Fig. 2). The outer portion of the 105 wall Z of this is removed (see Figs. 2 and 4). This is hereinafter called the combination driving tongue hole and driving tongue operator, inasmuch as by it the said tongue is radially operated within the tongue box here- 110

inafter referred to. Into this combination hole is passed the inner or headed end A¹ (Fig. 2) of a rectangular sectioned driving tongue B¹. The said driving tongue there-
fore protrudes radially from the said disk.

Attached between each of the cover plates H and J is the pump casing C¹. The interior of this is larger in diameter than the disk and there is existing between the disk and the interior of the casing a crescent-shaped space (see Fig. 2). Protruding from the outside of the casing is a tongue box D¹. The outer end of this is closed by a cover plate D². In this box is a radial passageway E¹ (see Fig. 1) to accommodate the outer end of the driving tongue which tongue moves in and out of the passageway radially as the casing and the pump disk rotate.

Inside the casing and at each side of the pumping disk is placed a ring F¹. In each such ring is a central hole F² which is larger than the spindle to allow of the eccentric travel of the said spindle. At the side of each ring is also a chamber G¹ into which escaping water passes. The inner surface H¹ of each ring F¹ is pressed against the disk side by adjusting screws J¹ passing through each cover. Through each ring F¹ is a discharge hole K¹ (see Fig. 2.)

To the circumference of the casing may be attached a driving ring L¹. This may accommodate a flat leather belt or may be provided with sprockets to accommodate a chain. Or it may be grooved to afford a rope guide. Or it may be toothed driven or the casing may be wound in such a manner as to form the armature of an electric motor, in which case it will be electrically driven.

Two of our pumps may be placed suction end to suction end as seen in Fig. 5. The stuffing boxes and the glands G then lead into the water chamber M¹. Into this the suction water through the inlet hole N¹ enters and passes into the suction spindles R. The spindles overhang the glands G as seen. Around each end is recessed a thrust plate O¹. The distance between the said thrust plates is adjusted by means of the adjusting bolts P¹. These are prevented from rotating by the stop Q¹ or other means. The said chamber is closed and provided with an inspection cover.

The cycle of operations with our invention is as follows.—The water is led to the suction

connection G³ on the suction gland and from there into the suction spindle R of the pumping disk T. It then passes through the suction passageway W outwardly till it reaches the suction port U when it is liberated into the space existing between the circumference of the said pumping disk T and the inner wall of the casing C¹. As this casing rotates the outer end of the driving tongue B¹ drives the inner or headed end A¹ of the same. This turns the pumping disk T so that the said disk and casing C¹ rotate together. The water drawn in through the suction spindle R as the casing rotates is compressed within the casing and finds exit through the discharge port V in the circumference of the said pumping disk T. It then passes inwardly through the discharge passageway X to the discharge spindle S and then through the connection G³. The chambers G¹ in the rings F¹ gather any water that may escape between the inner surface of the said ring and the surface of the disk. Centrifugal force throws this water through the discharge hole K¹ (Fig. 2) into the suction space in the casing. A similar action to the foregoing takes place when two suction ends are placed together as seen in Fig. 5 save that the suction water first enters the water chamber M¹ before it enters the suction spindles.

Having now described our invention what we claim as new and desire to secure by Letters Patent is.—

In a pump, a pair of brackets, each bracket having a stuffing-box and a gland in each stuffing-box, a boss on the inner side of each bracket, a shoulder on each boss, a cover plate for each boss; a leather washer having an enlarged end and retaining said cover plate in place, a plate securing said washer in place, and a locking ring surrounding the enlarged portion of said washer, in combination with a casing rotatably supported between said brackets, a suction disk rotatable with the casing, tubular suction and discharge spindles connected with said disk, and a driving tongue connected with said casing and with said disk.

In testimony whereof we affix our signatures in the presence of two witnesses.

MAURICE MOORE.
JOHN MURRAY.
